MULTIPLE UNIT TOWNHOUSE

Peter H. Edwards, Upper Arlington, Harvey R. Geiger, Columbus, and W. Byron Ireland, Upper Arlington, Ohio, assignors to Multicon Properties, Inc., Columbus, Ohio

Filed June 15, 1971, Ser. No. 153,486

Term of patent 14 years

Int. Cl. D25—03

U.S. Cl. D13—1 A

FIG. 1 is a front elevational view of a multiple unit townhouse showing our new design;

FIG. 2 is a rear elevational view;

FIG. 3 is an end elevational view looking toward the left end of the multiple unit townhouse as shown in FIG. 1;

FIG. 4 is an elevational view of the opposite end of the multiple unit townhouse; and

FIG. 5 is a top plan view thereof.

We claim:

The ornamental design for a multiple unit townhouse, substantially as shown.
